UNITED STATES PATENT OFFICE.

MOSES VOLNEY LIDDELL, OF HARVEY, ILLINOIS, ASSIGNOR TO AUSTIN MANUFACTURING CO., OF CHICAGO, ILLINOIS, A CORPORATION OF ILLINOIS.

STREET SWEEPER.

Application filed January 24, 1920. Serial No. 353,794.

To all whom it may concern:

Be it known that I, MOSES VOLNEY LIDDELL, a citizen of the United States, residing at Harvey, in the county of Cook and State 5 of Illinois, have invented certain new and useful Improvements in Street Sweepers, of which the following is a specification.

The present invention relates to street sweepers, and particularly to that portion 10 of the street sweeper which has to do with the gathering of material from an area to one side of the machine and bringing it beneath the machine where it will be encountered by other sweeping mechanism, so that 15 the machine will be adapted to work close up to a curb or other obstruction which prevents the main sweeping mechanism from reaching such surface.

The object of the invention is to provide 20 in combination with a broom constructed for rotation about a vertical axis, an improved mechanism for the mounting and control of such a broom.

The invention is designed primarily for 25 use in, a power-driven pick-up sweeper, but it will be obvious that the several features of novelty are adapted for other uses, and the illustrated embodiment of the invention is therefore not to be taken as a limitation.

In the accompanying drawings,

Figure 1 is a side elevation of the gutter sweeping attachment constituting the subject-matter of the present invention.

Figure 2 is a vertical axial section on an 35 enlarged scale of the suspending and elevating head of the sweeper shaft.

Figure 3 is a vertical sectional view of the gear box and mounting for the sweeper shaft.

The object of the present invention is to 40 mount the gutter sweeper of a sweeping machine, in the form of a broom G, upon an approximately vertical shaft 1 through which rotation may be imparted to the 45 broom, and by which the broom may be raised from the surface when not in use, or lowered when required to act. The shaft 1 is preferably inclined at such angle to the vertical as will develop contact with the 50 surface by the forward outer sector of the broom, thus causing the latter to displace the refuse forwardly and outwardly to a position beneath the machine, where it will

be left in position to be encountered by the main sweeping mechanism.

Shaft 1 is mounted to slide in a box 2 through means of which the gutter sweeper is mounted upon the frame F of the machine; said shaft being splined in the sleeve 3 (Figure 3), which is rotatably sustained 60 by radial bearings 4 in the box 2, so that the shaft may be driven by said sleeve 3 while permitting it freedom of vertical movement in the sleeve. Sleeve 3 sustains no material portion of the vertical load of 65 the shaft 1, but is itself sustained by means of its drive gear, which comprises the bevel pinion 5 mounted on the sleeve and the co-acting pinion 6 whose horizontal shaft 7 is positioned in radial bearings 8 and protrudes beyond the box to receive the driving 70 sprocket 9.

Bearings 4 are vertically sustained in the box 2, the upper one by shoulders 4^a, and the lower one by the spanner nut 4^b. Outer 75 bearing 8 is confined by the spanner nut 8^a and is preferably protected by packing 10 introduced between said nut and the bearing.

In order to control the shaft 1 vertically, 80 it is provided with a supporting and lifting head 11 which receives the reduced upper end 1^a of the shaft 1 with dust packing 12 and supports said end through the medium of a nut 13 and thrust bearing 14 interposed 85 between the nut 13 and the shoulder 11^a of the head. A cap 15 secured to the head 11 by screws 16 and carrying the center screw 17 develops downward pressure upon the shaft 1 to bring it under control of the head 90 11 in development of downward pressure of the broom. A pair of links 18 pivoted at 19 to the head and at 20 to the respective arms 21 of a bifurcated hand lever 22 (see Figure 1) form with the ends of said hand 95 lever a toggle lever connection through means of which the shaft and its broom may be not only raised from the surface but positively forced down upon the surface to insure proper sweeping contact. An adjustable arresting stop 23 that receives a projection on one of the arms 21 of lever 22 determines with exactness the extent of depression of the broom, and consequently its 100 sweeping effect; and a toothed rack 25 concentric with the lever fulcrum 26 on the

horn 26^a of box 2 receives the locking dog 27 of the lever 22 to hold the latter in any position to which it may be adjusted. Additional holes 20^a in the links 18 afford rough change in the depression of the shaft with its broom, and these together with the fine adjustment afforded by stop 23 permit the action of the broom to be controlled with exactness.

10 The broom preferably employed in connection with the present invention comprises a supporting disk 38 and wisps of splints 39, with means for mounting them upon the disk in a manner to be conveniently replaced and to remain securely held against angular displacement while in use. Accordingly, the disk 38 is formed with a depending frusto-conical flange 40 affording an outer inclined face against which the 20 wisps 39 may be laid and upon which they may be secured by means of bolts 41, and an abutment flange 42 which receives the upper ends of the wisps and secures the latter against displacement by vertical thrust. Bolts 41 carry clamping plates 43 through which they secure the wisps.

I claim:

1. In combination, a bearing box, a sleeve and a drive shaft mounted in said box, co-acting bevel pinions carried, respectively, by said drive shaft and sleeve, a driven shaft having splined sliding bearing in said sleeve, and means for longitudinally positioning said driven shaft comprising a supporting head in which the driven shaft is suspended and a controlling lever having connection with said supporting head; said connection comprising an arm on said lever and a link forming with said arm a toggle lever.

40 2. In combination, a bearing box, a sleeve and a drive shaft mounted in said box, co-acting bevel pinions carried, respectively, by said drive shaft and sleeve, a driven shaft having splined sliding bearing in said sleeve, 45 means for longitudinally positioning said driven shaft comprising a supporting head in which the driven shaft is suspended and a controlling lever having connection with said supporting head, and an adjustable stop for said lever.

50 3. In combination, a bearing box, a sleeve and a drive shaft mounted in said box, co-acting bevel pinions carried, respectively, by said drive shaft and sleeve, a driven shaft having splined sliding bearing in said sleeve, and means for longitudinally positioning said driven shaft comprising a supporting head in which the driven shaft is suspended and a controlling lever having 55 connections with said supporting head; said connection comprising an arm on said lever and a link forming with said arm a toggle lever; and said arm having an adjustable stop.

65 4. In combination, a bearing box, a sleeve

and a drive shaft mounted in said box, co-acting bevel pinions carried, respectively, by said drive shaft and sleeve, a driven shaft having splined sliding bearing in said sleeve, and means for longitudinally positioning 70 said driven shaft comprising a supporting head in which the driven shaft is suspended and a controlling lever having connection with said supporting head; said connection comprising an arm on said lever and a link 75 forming with said arm a toggle lever; said arm having a projection beyond its connection with said link, and having an adjustable stop coacting with said projection.

5. In combination, a bearing box, a sleeve 80 and a drive shaft mounted in said box, co-acting bevel pinions carried, respectively, by said drive shaft and sleeve, a driven shaft having splined sliding bearing in said sleeve, and means for longitudinally positioning 85 said driven shaft comprising a supporting head in which the driven shaft is suspended and a controlling lever having connection with said supporting head; said connection comprising an arm on said lever and a link 90 forming with said arm a toggle lever; said arm and link being adjustably connected to vary the throw of the driven shaft.

6. In combination, a bearing box, a sleeve and a drive shaft mounted in said box, co-acting bevel pinions carried, respectively, by said drive shaft and sleeve, a driven shaft having splined sliding bearing in said sleeve, and means for longitudinally positioning 95 said driven shaft comprising a supporting head in which the driven shaft is suspended and a controlling lever having connection with said supporting head; said connection comprising an arm on said lever and a link forming with said arm a toggle lever; said arm and link being adjustably connected to 100 vary the throw of the driven shaft; and said arm being provided with an adjustable stop to further vary said throw.

7. The combination of a driven shaft, a 110 head for sustaining said shaft, a thrust bearing in said head upon which said shaft is suspended, and means independent of said thrust bearing for imparting movement to said head in the direction of the axis of said shaft.

8. The combination of a rotary shaft, a box in which said shaft is mounted with freedom of longitudinal movement, and means for sustaining and positioning the 120 shaft longitudinally without restricting its rotation; said means comprising a head mounted upon and partaking of the longitudinal movements of the shaft, a set screw carried by said head and bearing coaxially 125 upon the shaft and transmitting thrust from the head to the shaft in one axial direction, and a rotary bearing carried by the head, surrounding the shaft, and moving and sustaining the latter in the direction opposite 130

to that of said thrust; the set screw being adjustable relatively to the bearing.

9. The combination of a driven shaft, a head for sustaining said shaft, a thrust bearing in said head upon which said shaft is suspended, a cap covering said thrust bearing and carrying a set screw pressing said

shaft upon said thrust bearing, and means for imparting movement to said head in the direction of the axis of said shaft.

10

Signed at Chicago, Illinois, this 20th day of January, 1920.

MOSES VOLNEY LIDDELL.
